UNITED STATES PATENT OFFICE.

JOHN J. VARUSKY, OF MINNEAPOLIS, MINNESOTA, ASSIGNOR TO CARTER-MAYHEW MANUFACTURING CO., OF MINNEAPOLIS, MINNESOTA, A CORPORATION OF MINNESOTA.

SCALPER.

Application filed August 17, 1927. Serial No. 213,518.

This invention relates to scalpers of the type disclosed and claimed in the prior Carter Patents Nos. 1,568,267, of date January 5, 1926, and 1,620,439, of March 8, 1927. In the scalpers of the said Carter patents and in this improved scalper, a coarse mesh endless traveling screen, preferably in the form of a cylindrical drum mounted to rotate on a horizontal axis, is employed, and the function of said screen in the handling of grain is to remove from the grain foreign materials such as sticks, pieces of binding twine, straw, pieces of paper, bark, leaves, twigs and the like, and most of which have at least two dimensions that are less than the openings in the screen. The openings in the screen are so large that good grain will freely pass therethrough.

In all of these scalpers, separation of the long foreign materials, such as noted, from the grain, requires a more rapid movement of the screen than of the grain and, hence, there is provided retarding means which intercepts the free flow of the grain and causes the same to bank up in more or less compact condition against the inner upwardly moving portion of the screen. The baffles or other devices for retarding the flow of the grain through the screen, of course, cause a corresponding slowing up of the separating or screening action. I have found, however, that the necessity for this retarding action may be reduced to a minimum and the most efficient scalping action can be produced by maintaining the top of the grain line between the feed hopper and the scalping screen at the highest possible point on the periphery of the screen, without overflowing the top and varying the thickness of the stream of grain by an adjustment of the lower point of delivery to the screen. This provides a minimum distance for the scalpings to be carried on the screen surface and, as a result, not only the long dimension scalpings, but foreign materials of all three dimensions smaller than the meshes of the screen, such as chunks of coal, for example, will usually be carried over and discharged as scalpings. The greater the distance between the grain line and the point of discharge, the greater the danger of the scalpings, that have been up-ended and separated out of the mass, falling back through the

screen and, consequently, passing out with the clean grain.

As an important feature, I provide an adjustable delivery deck, which receives the grain from the hopper or source of supply and delivers the same onto the upwardly moving surface of the rotary screen; and as a further highly important feature, I provide automatic means for adjusting this delivery deck in accordance with any variation in the supply or rate of flow of the grain into the supply or feed hopper. Otherwise stated, if the normal or average supply of grain to the hopper is increased, the delivery end or edge of the deck will be moved downward on the screen; and on the other hand, if said supply to the hopper be decreased, the delivery edge of the deck will be moved upward on the screen. Throughout such adjustments, the upper line of the grain delivery onto the screen will remain substantially constant, irrespective of adjustments of the deck.

As still another important feature, however, I provide the hopper with an adjustable gate by means of which the upper line of the grain flowing from the hopper to the screen may be varied. This latter noted adjustment is made highly important because of the fact that different kinds of grain will have different angles of repose. For example, the angle of repose of flax will be at a less angle to horizontal than will the angle of repose of wheat, and, on the other hand, the angle of repose of oats and barley will be at a greater angle to the horizontal than will the angle of repose of wheat. The hopper gate or grain-line-adjusting device will be set manually and so that the upper line of the flow of the grain from the hopper to the screen may be adjusted properly to the highest practical point of delivery to the screen.

The importance of the features and the operation of the devices above generally outlined will be more fully considered after first having described a commercial scalper involving my present invention.

In the drawings, which illustrate said commercial machine, like characters indicate like parts throughout the several views, and referring to said drawings,

Fig. 1 is a side elevation with parts broken away, showing the improved scalper;

Fig. 2 is a front to rear vertical section taken through the scalper on the line 2—2 of Fig. 3; and

Fig. 3 is a horizontal section taken approximately on the irregular line 3—3 of Fig. 2, some parts being broken away.

In the machine illustrated, the commingled grain, which may be assumed to be wheat containing more or less of the foreign materials above referred to as scalpings, is delivered by a spout 4, first into a hopper 5 and from thence into a main feed or supply hopper 6. The auxiliary hopper 5 is contained in the upper portion of the main hopper 6 and, as shown, is suspended from the top thereof by coiled springs 7. The main hopper 6 is shown as supported on top of a casing 8, preferably of sheet metal. The numeral 9 indicates a curved air conduit extended through the lower rear portion of the casing 8 below the hopper 6. This conduit 9 forms no part of the present invention and need not be further considered except to note that it happens to afford the support for a bracket 10 in which is journaled a fulcrum roller 11 on which is movably mounted the adjustable delivery deck 12 referred to in a general way in the introductory statements.

The main hopper 6 is provided with a discharge passage arranged to deliver onto the forward portion of the deck 12, to wit: onto that portion of said deck that is forward of the fulcrum 11; and said discharge passage is controlled by a sliding gate 13 shown as made adjustable by a pinion 14 that meshes with a rack 15 on said gate. The pinion 14 is on a transverse shaft 16 which may be adjusted and secured by any well known means, such as generally employed in hopper-gate-adjusting devices. Of course, any suitable means may be provided for adjusting the said gate.

At its rear edge, the delivery deck 12 is shown as connected by short links 17 to parallel arms 18 secured to a rock shaft 19 journaled in suitable bearings on the sides of the casing 8. At one outer end, the shaft 19 has short arms 20 that are pivotally connected to links 21, the upper ends of which latter are pivoted to trunnions 22 secured on the sides of the auxiliary hopper 5 and working freely through slots 23 in the sides of the casing 8. At one end, the rock shaft 19 is shown as provided with a lever 24 having a slotted segment 25, which, by a nut-equipped bolt 26 may, under certain conditions hereinafter stated, be tightened to lock the deck 12 and auxiliary hopper in set positions. In the automatic action hereinafter described, said nut-equipped bolt 26 will be loose so that it does not interfere with movements of the delivery deck, auxiliary hopper and intermediate connections. For a purpose which will hereinafter appear,

the rear portion of the deck 12 is pivotally connected to the rear ends of arms 27, the front ends of which are pivotally connected to the sides of the casing 8 at 28.

The endless moving screen, in the form of a horizontally disposed coarse mesh woven wire cylinder or drum 29, has heads 30 that are secured to a transverse shaft 31 journaled in suitable bearings in the sides of the casing 8. This rotary screen 29 is located within the casing 8 in position to receive the grain *y* delivered from the deck 12 against its upwardly moving portion at the highest possible point practicable. The shaft 31 at one end is shown as provided with a pulley 32, by means of which the screen may be power-driven and constantly rotated in a counterclockwise direction in respect to Fig. 2. Within the rotary screen are flow-retarding baffle plates 33. These baffle plates, as shown, are slightly curved, are eccentrically extended within said screen, are circumferentially spaced and overlapped, and are secured to the drum heads 30. The cylindrical rotary screen with these baffle plates is not herein broadly claimed; since the same is disclosed and claimed in the prior Carter Patent #1,620,439. Said baffle plates, however, as a minor improved feature, are provided on their concave surfaces with longitudinal grain-retarding flanges 34 that intercept the flow of grain on those plates that are turned with their concave surfaces upward.

To maintain close contact between the delivery edge of the delivery deck 12 and the exterior of the rotating screen, said deck is shown as provided with a flexible flap 12^a of rubber or any other suitable flexible material. To afford easy access to the exterior of the rotating screen 29, the casing 8 is shown as provided with a hinged door or cover section 8^a. Below the screen 29, the casing 8 is provided with a hopper-like discharge spout 8^b that receives the grain *y*, and with another hopper-like discharge spout 8^c that receives the scalpings *y'*.

Summary of operation.

Figure 2 illustrates what may be treated as an average or medium flow of grain, assumed to be wheat. Under this assumed average flow, there will be a slight accumulation of grain in the auxiliary hopper 5 and such depression of said hopper that the described connections between the same and the delivery deck 12 will set the latter in the position indicated by full lines in Fig. 2. By adjustment of the gate 13, the upper line of the flow of grain from the hopper 6 to the rotating screen 29 will be set substantially as shown, so that the scalpings will have only a short distance to travel over the top of the screen.

When the supply of grain into the auxili-

ary hopper 5 is increased so as to cause a further accumulation within the hopper 5, the latter will be moved downward farther than shown in Fig. 2 and will thereby cause 5 the delivery deck 12 to be adjusted substantially to the position shown by dotted lines in Fig. 2 so that the stream of grain of increased depth then flowing to the screen will be delivered against the screen at a lower 10 point without, however, changing the point of delivery of the upper portion of said screen. If, on the other hand, the flow of grain to the hopper should be decreased from that illustrated in Fig. 2, the accumulation in 15 the auxiliary hopper 5 will be reduced and the said hopper, under the action of the springs 7, will be raised so as to cause the delivery end of the deck 12 to move further upward on the screen than illustrated by full 20 lines in Fig. 2.

Under the above noted automatic adjustments of the delivery deck, the links 27 cause the deck to advance toward the upper portion of the screen as it is raised and to recede when it is lowered. Thus, the movement of the delivery edge of the deck is caused to follow a line that somewhat closely approaches the curved exterior of the rotating screen and the flexible flap 12^a will 30 take care of slight variations from a true circular movement.

Under rotation of the screen 29 in a counterclockwise direction, the baffle plates 33 will retard the flow of the grain through 35 the upper portion of the screen and, as before stated, will cause the same to bank up in more or less compact condition against the inner surface of said screen so as to give the screen a chance to act upon the scalplings and to remove the same from the stream of grain. Otherwise stated, the baffle plates serve as an efficient means for retarding the flow of the grain through the screen to such an extent that its movement will be slower in lineal 45 measurement than is the rotary travel of said screen.

In the above described machine, the scalping capacity of the screen is varied automatically in accordance with variations in the supply of grain to the hopper, and this is accomplished by automatic adjustments given to the delivery deck under an action produced by variations in the supply of grain to the hopper and while maintaining approximately a constant line of delivery of the upper portion of the grain to the screen, and which upper line of delivery of the grain, while adjustable, may be fixed or predetermined for the most efficient scalping of any 60 particular kind of grain.

In the operation of a modern flour mill, the flow of grain frequently shuts off completely. This would also frequently happen where scalpers are installed to scalp the 65 grain as it is unloaded from cars. In the

operation of the above described machine, under such conditions, when the supply of grain dwindles away or reaches nil, the upper edge of the delivery deck will be raised to such a high point on the screen that the 70 scalplings remaining on the screen after the supply of grain thereto has been cut off will be carried over by the screen and not permitted to reunite with the grain. The automatic adjustment of the delivery deck reduces to such an extent the required retardation or backing up of the grain against the screen that it is not necessary to have a gate or any other retarding means below the screen, and it also gives the machine a maximum 75 scalping efficiency and permits the grain to be delivered through the screen at a maximum rate of speed, thereby increasing the capacity of the machine or the amount of grain that can be run through the screen in 80 any unit of time.

Sometimes in the scalping of grain and especially when the supply to the hopper is constant, it may be desirable to lock or set the auxiliary hopper and delivery deck 90 in predetermined position, and this may be readily accomplished by tightening the nut-equipped bolt 26, thereby locking the lever 24 and the intermediate connections between the auxiliary hopper and deck against movement. 95

The term "hopper" is herein used in a broad and liberal sense to include any suitable container for the grain to be delivered to the screen. The term "delivery deck" is herein used in a broad and liberal sense to include any suitable device for receiving the grain from the supply means and for delivering the same to the screen. 100

What I claim is:

1. A scalping machine comprising an endless travelling scalping screen, a supply hopper, a delivery deck receiving from said hopper and delivering against the upwardly moving portion of said screen, said deck being adjustable for varying the depth of flow from the angle of repose to different points on said screen, and automatic means for adjusting said deck in accordance with the flow of the stock. 110

2. A scalping machine comprising an endless travelling scalping screen, a supply hopper, a delivery deck receiving from said hopper and delivering against the upwardly moving portion of said screen, said deck being adjustable for varying the depth of flow from the angle of repose to different points on said screen, and means subject to the flow of stock into said hopper and having connections to said delivery deck for adjusting the latter and arranged to raise the delivery edge of said deck under decreasing supply of stock and to lower the delivery edge of said deck under increasing supply of stock. 120

3. A scalping machine comprising a drum-like screen arranged to rotate on an approximately horizontal axis, a supply hopper, a delivery deck receiving from said hopper and delivering against the upwardly moving portion of said screen, said deck being mounted for angular adjustments in a vertical plane for varying the depth of flow from the angle of repose to different points on said screen, and means subject to the flow of stock and having connections to said deck for vertically adjusting the latter and arranged to raise the delivery edge of said deck under decreasing supply of stock and to lower the delivery edge of said deck under increasing supply of stock.
4. In a scalping machine, the combination with a main hopper and an auxiliary hopper yieldingly suspended for delivery thereto, of a drum-like rotary screen, a delivery deck receiving from said main hopper and mounted for adjustments to vary the depth of flow from the angle of repose to different points on said screen, and a connection between said auxiliary hopper and deck arranged to cause the delivery edge of said deck to lower when said auxiliary hopper is depressed, and conversely, to cause the delivery edge of said deck to rise when said auxiliary hopper is raised from an intermediate position.
5. The structure defined in claim 4 in

which said connections between said auxiliary hopper and deck include a rock shaft with arms, certain of which are connected to said deck and certain of which are directly connected to said auxiliary hopper.

6. The structure defined in claim 4 in which said connections between said auxiliary hopper and deck include a rock shaft with arms, certain of which are connected to said deck and certain of which are directly connected to said auxiliary hopper, and other links connected to said deck for imparting edgewise movement thereto when said deck is given angular adjustments.

7. A scalping machine comprising a rotary scalping screen, a supply hopper, and a delivery deck receiving from said hopper and delivering against the upwardly moving portion of said screen, said deck being adjustable for varying the depth of the flow from the angle of repose to different points on said screen, said hopper having an adjustable gate for variably determining the upper line of flow of grain from said hopper to said screen.

8. The structure defined in claim 2 in which said hopper has an adjustable gate for variably determining the upper line of flow of grain from said hopper to said screen.

In testimony whereof I affix my signature.
JOHN J. VARUSKY.
